UNITED STATES PATENT OFFICE.

JOHN S. BRENNAN, OF MILWAUKEE, WISCONSIN.

BURNER DRUM.

Application filed December 3, 1919. Serial No. 342,166.

To all whom it may concern:

Be it known that I, JOHN S. BRENNAN, a citizen of the United States, and resident of Milwaukee, in the county of Milwaukee 5 and State of Wisconsin, have invented certain new and useful Improvements in Burner Drums; and I do hereby declare that the following is a full, clear, and exact description thereof.

10 My invention relates to new and useful improvements in the combustion drums of oil burners, more particularly of that type adapted for use in domestic cooking stoves and comprising a pair of concentric perforated tubes extending upwardly from an annular wick head, the tubes being surrounded by an imperforate casing. In this type of device, the oil is vaporized and the resultant vapor rises in the annular space between the tubes, the process of combustion being carried on throughout this annular space and at the top of the tubes. In this type of structure, there exists a tendency for the inner tube to suffer disintegration 15 due to the action of excessive heat generated in the drum, and the upper end portion of the inner perforated tube is particularly liable to disintegration.

It is in general the object of my invention to improve the combustion action of burner drums of this character with respect to the procurement of a complete combustion of the vapor gases and an even distribution of the flame at the top of the burner 20 drum, and it is more particularly my object to prevent excessive heating of any portions of the perforated tubes, while at the same time maintaining an even and free flow of air through the inner tube so as to insure completion of the combustion action 25 at the top of the burner drum.

With the above and other objects and advantages in view, which will be apparent as the description proceeds, my invention 30 resides in the novel features of construction, combination and arrangement of parts which will be hereinafter more particularly described and defined by the appended claims.

35 In the accompanying drawing:

The figure shows a vertical sectional view through a burner drum constructed in accordance with my invention.

Referring now more particularly to the 40 drawing, I have shown the usual annular wick trough 5 having a non-combustible

wick section 6 disposed therein and projecting slightly above seating ledges formed by laterally turning the upper edge portions 7 of the trough, the trough 5 being provided 45 with the usual depending supply stem 8. The usual inner and outer perforated combustion tubes 9 and 10 respectively have their lower ends seating on the ledges 7, the tubes being held in concentric spaced relation by the usual cross-rods 11 passed through their upper portions, said rods also supporting the usual outer casing member 12 having an inturned perforated flange 13 at its lower edge and having an inturned 50 frustoconical flange 14 at its upper end which is equal in width substantially to the distance between the walls of the casing 12 and the outer tube 10. A partition 15 extends across the top of the space enclosed 55 by the wick trough 5, this partition being perforated to permit free passage of air therethrough, but at the same time break up any positive currents which might tend to interfere with the even passage of combustion gases within the tube space, and a centrally perforated plate 16 is disposed 60 within and secured to the lower portion of the inner perforated tube 9.

Practice has demonstrated, that in the 65 aforesaid conventional structure, a certain flow of air entirely through the inner combustion tube 9 is necessary to insure completion of the combustion action at the top of the drum, while an excessive flow 70 of air therethrough will procure such active combustion conditions immediately adjacent the inner tube 9 as to raise said tube to a white heat and thus set up those processes which procure disintegration of the 75 tube. It is therefore highly important to carefully control and direct the amount of air passing through the inner tube 9, and in carrying out my invention I provide a slightly frustoconical plate 17 having its 80 peripheral portion upwardly turned to fit within the top of the combustion tube 9, said peripheral portion of the plate being further bent to embrace the upper edge of the tube and thus support the plate. The upper 85 edge of the tube 9 is spaced a slight distance below the upper edge of the outer tube 10, and a substantially frustoconical section 18 is seated on the plate, with its top extending approximately to the plane 90 of the upper edge of the frustoconical casing flange 14, the wall of this frustoconical 95

section 18 having an ogee curvature in cross section. The plate 17 is provided with a central aperture 19 and is bent to provide an annular reinforcement about said aperture, and the section 18 is provided in its top with a slightly smaller central aperture 20.

Entering now into the operation of my improved structure, it is noted that the usual free supply of air is permitted between the casing 12 and the outer combustion tube 11, while a moderate supply of air is admitted through the perforated partition 15 to the interior of the inner combustion tube 9, and air may enter the annular space between the tubes and commingle for combustion with the oil vapor in said space through the perforations of the tubes throughout their entire lengths. By providing a series of centrally apertured plates within the combustion tube 9, a fairly free flow of air is provided through the center of the space enclosed by the tube, while the flow of air immediately adjacent the inner surface of the tube is retarded, to thus discourage active combustion processes immediately adjacent the surface of the tube which would tend to procure an excessive heating of the inner tube to a white hot condition. At the same time, the free flow of air through the central portion of the space enclosed by the tube 9, which is permitted by the central apertures of the various plates and frustoconical section 18, will supply a current centrally at the top of the drum which will finish the combustion process in a complete manner, and this current of air will tend to draw combustion gases inwardly from the top of the annular space between the tubes, thus spreading the flame action over the top of the drum by reason of the frustoconical section 18. It will be further noted that the sum of the areas of the apertures of the burner trough partition 15 is greater than the area of the aperture of the plate 16 which in turn is greater than the area of the aperture of the plate 17, this latter area being in turn slightly greater than the area of the aperture 20 of the frustoconical section

18, thus providing for a gradual decrease in the diameter of the air column extending through the space defined by the inner tube 9.

While I have shown and described a preferred embodiment of my invention, it will be appreciated that various changes and modifications of structure may be employed to meet differing conditions of use, without departing in any manner from the spirit of my invention.

What is claimed is:

1. In a burner structure of the class described, in combination, a pair of upstanding concentric perforated tubes, a plate extending across the top of the inner tube, said plate being provided with a central aperture and a section of substantially frustoconical shape having its base portion seated on the peripheral portion of the plate and having a central aperture slightly smaller than the aperture in the plate.

2. In a burner structure of the class described, in combination, a pair of upstanding concentric perforated tubes, a plate extending across the top of the inner tube and provided with a central aperture and being imperforate adjacent the wall of the inner tube, and a substantially frustoconical section disposed above the plate and provided with a central aperture.

3. In a burner structure of the class described, in combination, a pair of upstanding concentric perforated tubes, a plate extending across the top of the inner tube, said plate having its peripheral portion upwardly turned to fit in the top of the tube and then outwardly turned to seat on the tube, said plate being provided with a central aperture, and an apertured section of substantially frustoconical shape having its base portion seated on the peripheral portion of the plate.

In testimony that I claim the foregoing I have hereunto set my hand at Milwaukee, in the county of Milwaukee and State of Wisconsin,

JOHN S. BRENNAN.
